UNITED STATES PATENT OFFICE.

THOMAS F. FEHRLE, OF PHILADELPHIA, PENNSYLVANIA.

HOPPER.

1,346,310.

Specification of Letters Patent. Patented July 13, 1920.

Application filed February 12, 1919. Serial No. 276,599.

To all whom it may concern:

Be it known that I, THOMAS F. FEHRLE, a citizen of the United States, residing at Philadelphia, in the county of Philadelphia 5 and State of Pennsylvania, have invented certain new and useful Improvements in Hoppers, of which the following is a specification.

My invention relates to improvements in 10 hoppers and particularly relates to hoppers to be used in connection with machinery for treating wool.

The object of my invention is to construct a hopper through which a greater amount 15 of material may be passed, within a given time than heretofore by reason of its improved construction; a further object of my invention is to construct a hopper having the air inlet and the conveyer outlet apertures formed within the converging walls of the hopper, and thus dispensing with the usual form of vertical throat below the converging walls of the hopper, which throat tends to clog the hopper; and a still further 25 object of my invention is to admit the air blast from the air supply pipe directly into the angular portion of the hopper so that the air blast can keep the wool in the hopper agitated and force it through the hopper 30 with greater speed than is possible when the hopper is constructed with a throat portion between the hopper proper and the discharge opening of the conveyer pipe. By my improved construction of the hopper economy 35 of space is obtained, as a low-down type of hopper is thus provided, which may be used in connection with a machine having the discharge opening close to the floor level.

Referring to the accompanying drawings; 40 Figure 1, is a perspective view of my improved hopper shown in use with a wool drier; Fig. 2, is a plan view of the hopper; Fig. 3, is a side view of the hopper, partially in section; and Fig. 4, is an end view of the 45 hopper.

In the accompanying drawings in which like reference characters refer to like parts, the hopper 1, consists of the sloping side walls 2 and 3 and the end walls 4 and 5. 50 The converging walls of the hopper form an inverted truncated pyramid. The side walls 2 and 3 of the hopper, are continuous and form a curved bottom portion 6, connecting the side walls 2 and 3.

55 The walls of the hopper are constructed of sheet metal and are reinforced by a rec-

tangular top frame 7, formed of angle-iron, and also by the supporting members 8, also of angle-iron. The supporting members 8 are substantially U-shaped, as shown in the 60 end view Fig. 4, having a lower base portion 9 and side portions 10, which latter embrace the side walls of the hopper and are connected with the top frame 7.

The air inlet pipe 12 and the outlet conveyer pipe 13 are in alinement and the axes thereof are entirely within the polyhedral angle formed by the converging walls of the hopper. The end walls 4 and 5 have openings formed therein at the places where the 70 pipes 12 and 13 are attached thereto and the said openings formed in the end walls are located between the apex and the base of the polyhedral angle.

The bottom portion 6 of the hopper is on 75 the same level with the lower portion of the pipes 12 and 13 and thus forms a continuous bottom surface between the inlet pipe 12 and the outlet pipe 13.

The air as it is forced through the inlet 80 pipe 12 strikes the deflector plate 15, and is directed toward the bottom portion of the hopper and carries the wool from the hopper into the outlet conveyer pipe 13.

By this construction of the hopper an ex- 85 cess accumulation of wool in the hopper will not clog the mouth of the outlet pipe 13, as the flaring walls of the hopper permit the mass of material to expand as it is lifted by the air from the inlet pipe 12.

In Fig. 1, the hopper is shown located at 90 the discharge outlet of a wool drier 20, in which the wool is dried by being conveyed through the drier upon the conveyer tables 21, in the usual manner.

Having thus described my invention I 95 claim and desire to secure by Letters Patent:

1. A hopper comprising flaring walls, a bottom portion connecting the flaring walls, an outlet conveyer pipe connected with the 100 hopper above the apex of the angle formed by the said walls of the hopper, an air inlet pipe connected with the hopper, a deflector plate located within the inlet pipe adjacent to the end thereof attached to the 105 hopper, and said deflector plate inclined at an angle to direct the air toward the bottom of the inlet pipe and the bottom of the hopper.

2. A hopper comprising flaring side walls, 110 a curved bottom portion connecting the side walls, flaring end walls connected with the

PFB

said side walls, said end walls extending to the said bottom portion and having openings formed therein, horizontal pipes having angular mitered ends corresponding to the angle of the end walls and connected with the end walls, said pipes registering with the said openings formed in the end walls, said pipes located on the same level with

the bottom portion of the hopper, and reinforcing frame members attached to the 10 hopper.

In testimony whereof I affix my signature in the presence of a witness.

THOMAS F. FEHRLE.

Witness:

MARTHA H. QUINN.
